(57) **CLAIM**

The ornamental design for a service station canopy rim, as shown and described.

DESCRIPTION

FIG. 1 is a perspective view of a service station canopy rim in accordance with the present design;

FIG. 2 is a side elevational view of the service station canopy rim of FIG. 1;

FIG. 3 is a front elevational view of the service station canopy rim of FIG. 1;

FIG. 4 is a top plan view of the service station canopy rim of FIG. 1; and,

FIG. 5 is a bottom plan view of the service station canopy rim of FIG. 1.

All broken lines illustrated in the drawings designate environmental structure.
